[57] CLAIM

The ornamental design for an optical disc player com-
bined with a radio receiver, as shown and described.

DESCRIPTION

FIG. 1 is a top plan view of an optical disc player com-
bined with a radio receiver showing my new design;
FIG. 2 is a left-side elevational view thereof;
FIG. 3 is a front elevational view thereof;
FIG. 4 is a right-side elevational view thereof;
FIG. 5 is a rear elevational view thereof;
FIG. 6 is a bottom plan view thereof;
FIG. 7 is a top, front and right-side perspective view
thereof; and,
FIG. 8 is a top, front and right-side perspective view
thereof, showing the aerial in an extended position.

FIG. 1
